UNITED STATES PATENT OFFICE.

GUSTAVE DEMARTIAL, OF LIMOGES, FRANCE.

DESIGN FOR A DISH.

SPECIFICATION forming part of Design No. 19,975, dated July 1, 1890.

Application filed June 4, 1890. Serial No. 354,288. Term of patent 14 years.

To all whom it may concern:

Be it known that I, GUSTAVE DEMARTIAL, a citizen of France, residing at Limoges, in the Department of Haute-Vienne, Republic of France, have invented and produced a new and original Design for Dishes, of which the following is a specification, reference being had to the accompanying drawings, forming a part thereof.

10 Figure 1 represents the side view of a soup-tureen. Fig. 2 is the side view of a covered dish. Fig. 3 is the face view of a cover. Fig. 4 is the face view of a platter or deep dish. Fig. 5 is the face view of a plate, these five views being deemed necessary to fully illustrate my design.

15 The leading feature of my design consists in the low oval form of the dishes having undulating edges divided into larger and smaller inclosures with handles representing bunches or sprays of chrysanthemum leaves and flowers.

20 The form of the soup-tureen and covered dish, Figs. 1 and 2, is low and oval.

25 The handles A A A represent a raised bunch or spray of chrysanthemum leaves and flowers, the stems being bound by a ribbon with streamers extending over the side of the dish.

30 Fig. 3 represents a face view of the cover,

which has undulating edges, giving also a full view of the handle A, which represents a bunch or spray of chrysanthemum leaves and flowers, as above described.

Beneath the handle on the top of the cover 35 there is a slight depression B.

The platter or deep dish, Fig. 4, is also oval, the circumference is undulating, and is divided into eight inclosures—two large D D, four small C C C C, and two medium E E. At 40 each end of the platter or deep dish there is a handle in relief of the same design as the handles on the soup-tureen or covered dish, above described.

Fig. 5 represents the plates, which are round 45 with scalloped edges divided into eight inclosures—four large F F F F and four small G G G G.

What I claim is—

1. The design for dishes, substantially as 50 herein shown and described.
2. In the design for dishes herein shown and described, the handles representing bunches or sprays of chrysanthemum leaves and flowers.

GUSTAVE DEMARTIAL. [L. S.]
